CLAIM

We claim the ornamental design for a lollipop-shaped pet toy, as shown.

DESCRIPTION

FIG. 1 is a perspective view of a lollipop-shaped pet toy showing our new design;

FIG. 2 is a front view thereof;

FIG. 3 is a rear view thereof;

FIG. 4 is a top plan view thereof, the bottom plan view being a mirror image; and,

FIG. 5 is a side elevation view thereof, the opposite side being a mirror image.
